CARBURETOR

Robert F. Bracke, Chicago, Ill.

Application February 1, 1935, Serial No. 4,479

18 Claims. (Cl. 261—34)

This invention relates to carburetors adapted to supply carbureted fuel to internal combustion engines and the like.

One of the objects of the invention is to provide an improved carburetor.

A further object of the invention is to provide an improved carburetor of the fuel lift type.

A further object of the invention is to provide a carburetor of the fuel lift type in which the 10 degree of fuel lift vacuum is modified under idling conditions to provide an automatic self-compensating idling control.

A further object of the invention is to provide an improved downdraft carburetor.

15 A further object of the invention is to provide an improved carburetor having an expanding Venturi tube which automatically adjusts itself to different conditions of engine operation.

20 Other objects, advantages, and capabilities of the invention will appear from the following description of a preferred embodiment thereof, taken in conjunction with the accompanying drawing, which shows in cross-section, a carburetor embodying my invention.

25 Referring to the drawing, the carburetor comprises two principal portions 10 and 11 which may suitably be castings. The upper portion 10 comprises a relatively large cylindrical mouth 12 which serves for the admission of air. The mouth 12 is provided with a spider 13 which supports a central hub 14. The hub 14 is bored axially, the lower portion of the bore being threaded to receive the exteriorly threaded surface of the primary Venturi tube or nozzle 15, which is directed 30 downwardly. The upper end of the Venturi tube 15 is provided with a shoulder 16 which engages the upper face of the hub 14. The hub 14 and Venturi tube 15 are conformed to provide an annular chamber 17 around the throat of the 35 Venturi tube. Fuel supply jets 18, which are preferably sloped inwardly and downwardly, extend between the annular chamber 17 and the throat of the Venturi tube 15.

The annular chamber 17 communicates 40 through a duct 19, which may extend through one of the spokes of the spider 13, with a vertical bore 20. The lower portion of this bore 20 is enlarged to receive a depending guide tube 21 and its intermediate portion is threaded to receive a 45 plug 22, the upper end of which is provided with a relatively large metering orifice 23 for the passage of liquid fuel. The guide tube 21 may be secured within the lower portion of the vertical bore 20 in any suitable way. It is, however, preferred to secure the tube 21 to the casting 10 by

means of the plug 22, which may be provided at its lower end with a flange which engages an inwardly extending flange at the upper end of the tube 21.

An economizer pin 24 is adapted to project upwardly through the orifice 23. At its lower end the pin is secured to an inverted cup 25 which has a sliding fit in the tube 21. Above the cup 25 a relatively weak coil spring 26, of large diameter, is provided. This spring abuts against the flange at the upper end of the tube 21 so as to tend to move the cup 25 and pin 24 downwardly. The upper end of the pin 24 is provided with an enlarged head 27 which is located within the orifice 23 during the part throttle range of the carburetor, corresponding to speeds between idling and, for example, sixty-five miles an hour. In this range the clearance between the head 27 and the metering opening 23 is relatively small so that only a restricted passageway for fuel is provided. Below the head 27 the pin 24 comprises a restricted portion 28, which portion is located within the orifice 23 when the throttle is wide open, as will hereinafter be described. The cup 25 is provided with an opening 29 which permits fuel to pass upwardly therethrough. The opening 29 is sufficiently small so that the cup 25 serves as the accelerator pump, supplying an increased amount of fuel when the accelerator is moved rapidly.

The upper portion 10 of the carburetor comprises a relatively flat member 30 which serves as a cover for the fuel chamber 31 which is provided in the lower portion 11 of the carburetor. It will be understood that these two portions of the 35 carburetor are assembled together in any suitable manner, a gasket 32 being provided between the contacting surfaces.

The lower portion 11 of the carburetor comprises a stepped cylindrical body 34 which is located in alignment with the cylindrical mouth 12. The fuel chamber 31, which is located below the flat member 30 and the bore 20, is located alongside the stepped cylindrical body 34. The throttle valve 35 which may be a butterfly valve 40 of the usual type, is located within the lower narrower portion of the stepped cylindrical body 34. A sleeve 36 is slidably mounted within the cylindrical body 34, being provided with an annular bearing surface 37 which has a sliding fit 45 in the lower portion of the stepped cylindrical body 34 and an annular bearing surface 38 of greater diameter which has a sliding fit within the upper enlarged portion of the stepped cylindrical body 34. The sleeve 36 and stepped cy- 50

lindrical body 34 provide between them a chamber 39, in which is provided a coil spring 40 normally tending to press the sleeve 36 upwardly so that its upper edge is brought into sealing engagement with the hub 14 of the spider 13. A duct 41 extends from the chamber 39 to the interior of the sleeve 36, opening thereinto preferably at a point near the upper end of the sleeve. The fuel chamber 31 is provided with a float 44 which controls a fuel inlet valve (not shown) in known manner. The bottom wall of the fuel chamber 31 is provided with an elongated vertical sleeve 46 which receives a rod 47 adapted to bear upon the upper wall of the inverted cup 25 at or near its center. The lower end of the rod 47 rests upon an arm 48 pivotally mounted on the body of the carburetor at a suitable point. Intermediate its pivotal point and the point of contact with the rod 47, the arm 48 rests on a cam 49 which is mounted on the shank of the throttle valve 35 outside the stepped cylindrical body 34. The cam 49 is configured so that when the throttle valve 35 is opened the arm 48 is raised to elevate the head 27 of the pin 24 within the metering orifice 23. At a predetermined throttle opening the head 27 emerges from the orifice 23 and the clearance between the reduced portion 28 of the pin 24 and the opening 23 provides an enlarged passage for the liquid fuel to meet the great demand for power at high speeds. It will be noted that the pin 24 is not positively connected to the rod 47 and that there is no necessity for exact alignment between the rod 47 and the elements associated with the pin 24 carried by the upper portion 10 of the carburetor. The tube 21 provides a large and accurate bearing for the cup 25 so that the pin 24 can readily be mounted and maintained in coaxial relation with the opening 23. The tube 21 projects below, and the sleeve 46 projects above the normal fuel level of the fuel chamber 31, defined by the float 44.

At one side, for example, the side opposite the fuel chamber 31, the stepped cylindrical body 34 is provided with a solid wall of enlarged thickness designated 50. This wall is provided with a transverse bore 51 for the accommodation of the fuel lift or booster Venturi tube 52. The inner end of the bore 51 is reduced slightly as shown at 53. The adjacent portion of the bore 51 is threaded so as to receive the correspondingly threaded portion of the Venturi tube 52. On the inner side of the head 54 of the Venturi tube 52, the bore 51 and the Venturi tube 52 are 55 conformed to provide an annular passageway 55 which surrounds the throat of the Venturi tube 52 and communicates therewith through openings 56. The outer end of the bore 51 is enlarged so as to receive the head 54 of the Venturi tube 60 52 and provide a chamber 57. A duct 58 connects the annular passage 55 to the upper portion of the fuel chamber 31. A duct 59 extends downwardly from the chamber 57 to a point below the throttle valve 35. The duct 59 is connected by 65 a duct 60 to the interior of the stepped cylindrical body 34 below the closed position of the throttle valve 35, and preferably at a point closely adjacent said valve.

The effective area of the duct 60 is controlled 70 by a needle valve 62 which is provided with a milled head whereby it may readily be adjusted. The wall 50 is provided with a flat outer face 64 which contains the outer end of the chamber 57. A duct 65 extends from the flat face 64 into 75 the annular chamber 39. A plate 66 is pivotally

mounted on the flat face 64 by means of a screw 67, a spring 68 serving to hold the plate 66 against the face 64. The plate 66 is provided with a metering orifice 69 adapted to register with the chamber 57 during the normal operation of the engine to which the carburetor is attached. The plate 66 is connected to suitable means (not shown) for its operation in the usual manner of operating a choke. When thus operated, the metering orifice 69 is brought out of register with the chamber 57 so that the Venturi tube 52 is rendered inoperative for the time being. The plate 66 is provided with an opening 70 which is adapted to be brought into register with the duct 65 in the choked position of the plate 66. 10 15

In the normal operation of the carburetor with the engine running, the metering orifice 69 is in register with the chamber 57 and the opening 70 is out of register with the duct 65, which is consequently closed, the throttle 35 is partly open, and the rod 47 and pin 24 are slightly elevated above the position shown in the drawing. The suction of the motor is sufficient to move the sleeve 36 downwardly somewhat away from seated relation with the hub 14 of the spider 13, so that secondary air is admitted through the mouth 12, the sleeve 36 and stepped cylindrical body 34 into the intake manifold of the engine. Air drawn through the Venturi tube 52 by the suction of the engine creates a vacuum in the duct 58 which is communicated to the fuel chamber 31. This vacuum in the fuel chamber effects the elevation of liquid fuel from the main fuel tank in known manner, the float 44 closing the valve (not shown) when a predetermined level is attained. In this way a constant level of fuel is maintained in the chamber 31. 20 25 30 35

With variations in engine suction, the vacuum or pull created by the Venturi tube 52 tends to vary considerably. The air flowing through the Venturi tube 52 impinges upon the lower end of the sleeve 36 which is slightly reduced below the bearing surface 37 to provide clearance for the passage of air downwardly towards the throttle valve 35. This reduced portion of the sleeve 45 tapers downwardly slightly, as shown in the drawing. This sleeve introduces resistance to the flow of air through the Venturi tube 52 and this resistance is increased at high speeds owing to the lower position of the sleeve 36, which results in the narrowing of the passage between the sleeve and the wall and also increases the length of restricted travel between the discharge of the air at 53 until it is mixed with the main stream floating downwardly past the throttle valve 35. As a consequence, the vacuum in the fuel chamber 31, while it increases progressively with increase of engine speed, does not increase at as great a rate as it would if the action of the Venturi tube were not modified in this manner. 50 55 60 65

The suction of the engine is partly satisfied by the secondary air entering the sleeve 36 around the hub 14, and partly by the rich mixture of air and fuel delivered by the Venturi tube 15. The primary air is drawn through the Venturi tube 15 65 by the suction of the engine and the momentum of the secondary air entering the mouth 12 imparts an initial velocity to the primary air which increases the efficiency of the Venturi tube 15. The Venturi tube 15 elevates fuel through the tube 21, the opening 29 in the cup 25, the opening 23 in the plug 22, and duct 19. At normal driving speeds, for example, from idling up to about sixty-five miles an hour, the head 27 of the economizer pin 24 is in the metering orifice 70 75 80 85 90 95

23. At greater speeds the head 27 is above the opening 23 and a less restricted passageway is provided for the liquid fuel.

The suction of the engine within the sleeve 36 extends through the duct 41 into the annular chamber 39 and causes a downward movement of the sleeve 36, against the action of the spring 40, proportionate to the intensity of the engine suction.

10 An important feature of my invention is the automatic self-compensating idling control. In order to understand this control, it is first necessary to appreciate certain fundamental relationships. The amount of fuel supplied by the Venturi tube or nozzle 15 is dependent both upon the volume of air flowing through this tube and also upon the degree of suction existing in the fuel chamber 31, so that by varying the degree of suction in the fuel chamber 31 the amount of 20 fuel supplied by the Venturi tube 15 can be varied for any given amount of air flowing therethrough.

The degree of suction existing in the fuel chamber 31 is controlled by the booster Venturi tube 54 and is proportional to the volume of air flowing through this booster tube. The volume of air flowing through this booster tube 54 in turn depends upon difference in pressure at the ends of this tube, and I vary the degree of suction existing in the fuel chamber 31 and therefore the 30 amount of fuel supplied by the Venturi tube 15, by varying the pressure differential between the ends of the booster Venturi tube 54. The Venturi tube 54 derives its air supply from the chamber 57 which communicates with atmosphere through metered orifice 69 which restricts the flow of air into the chamber 57. The chamber 57 is also connected to that part of the manifold on the engine side of throttle valve 35 by means of passageways controlled by needle valve 62.

40 When the throttle valve 35 is substantially open, there is very little suction communicated to chamber 57 by means of the passageways controlled by needle valve 62, but when the throttle valve 35 is moved to idling or substantially closed 45 position, the manifold vacuum rises and consequently the suction existing in the chamber 57 is increased, thereby decreasing the degree of suction in the fuel chamber 31 and permitting the Venturi tube 15 to supply a richer mixture. The carburetor is adjusted by means of the needle valve 62 so that a rich mixture is supplied to the engine at idling speed.

If the mixture supplied to the engine during idling should temporarily become lean for any reason, such, for example, as the passage of a 55 small amount of vapor instead of liquid fuel to the passages 18 in the Venturi tube 15, the effect of this lean mixture will be to cause the engine to speed up slightly. This speeding up creates 60 a higher degree of suction in that part of the manifold on the engine side of the throttle valve, and this higher degree of suction is communicated to the chamber 57 through passages 59 and 65 60. The resulting increase in suction in chamber 57 reduces the pressure drop across the Venturi tube 54 and this in turn reduces the degree of suction obtaining in the fuel chamber 31. Accordingly, fuel feeding nozzle 15 draws more fuel from fuel chamber 31 and supplies a richer mixture to the engine, thus causing it to slow down again and resume its normal idling speed.

In a similar manner my improved idling control will compensate for temporary increases in the richness of the mixture by causing corresponding increases in the degree of suction ex-

isting in the fuel chamber 31, thereby reducing the richness of the mixture supplied by the fuel feeding Venturi tube 15. This leaning of the mixture speeds up the rotation of the engine and re-establishes normal idling speed.

5 When the plate 66 is moved to choked position, the chamber 39 is put in communication with the atmosphere through the duct 65 and opening 70. The chamber 57 is closed by the plate 66 and the Venturi tube 52 is rendered inoperative as a 10 booster so that the degree of suction obtaining in the fuel chamber 31 becomes equal to that existing in the mixing chamber. Consequently, the suction of the engine draws a very rich mixture through the Venturi tube 15 and ease of start- 15 ing results.

20 Although the invention has been described in connection with the specific details of a preferred embodiment thereof, it must be understood that such details are not intended to be limitative of 20 the invention except in so far as set forth in the accompanying claims.

Having thus described my invention, what I claim as new and desire to secure by Letters Patent of the United States is:

25 1. A downdraft carburetor comprising a stepped body, a sleeve having a pair of bearing surfaces of different diameters slidable in said body and providing a chamber of variable capacity between said sleeve and body, a spring tending to force 30 said sleeve upwardly, a downwardly directed Venturi tube mounted in the upper part of said body, and means surrounding said Venturi tube adapted to receive the upper end of said sleeve to exclude secondary air, said sleeve having an opening establishing communication between said chamber and a point within said sleeve.

35 2. A downdraft carburetor comprising a stepped body, a sleeve having a pair of surfaces of different diameters slidable in said body and providing a chamber of variable capacity between said sleeve and body, a spring tending to force 40 said sleeve upwardly, a downwardly directed Venturi tube mounted in the upper part of said body, means surrounding said Venturi tube 45 adapted to receive the upper end of said sleeve to exclude secondary air, said sleeve having an opening establishing communication between said chamber and a point within said sleeve, and said body having an opening establishing communication between said chamber and the atmosphere, and means adapted to be actuated to open and close said last-mentioned opening at will.

50 3. A downdraft fuel lift carburetor comprising a stepped body, a sleeve having a pair of bearing surfaces of different diameters slidable in said body and providing a chamber of variable capacity between said sleeve and body, a spring tending to force 55 said sleeve upwardly, a downwardly directed Venturi tube mounted in the upper part of said body, means surrounding said Venturi tube adapted to receive the upper end of said sleeve to exclude secondary air, said sleeve having an opening establishing communication between said chamber and a point within said 60 sleeve and said body having an opening establishing communication between said chamber and the atmosphere, a fuel lift Venturi tube discharging into said body, and means adapted to be actuated at will either to open the last-mentioned 65 opening and close the fuel lift Venturi tube or to close said last-mentioned opening and open the fuel lift Venturi tube.

70 4. A downdraft fuel lift carburetor comprising a stepped body, a sleeve having a pair of bear-

- ing surfaces of different diameters slidable in said body and providing a chamber of variable capacity between said sleeve and body, the lower end of said sleeve being of reduced diameter to provide a clearance between it and the adjacent portion of the body, a spring tending to force said sleeve upwardly, a downwardly directed Venturi tube mounted in the upper part of said body, means surrounding said Venturi tube adapted to receive the upper end of said sleeve to exclude secondary air, said sleeve having an opening establishing communication between said chamber and a point within said sleeve and said body having an opening establishing communication between said chamber and the atmosphere, a fuel lift Venturi tube discharging into said body the discharge from which is adapted to impinge against said reduced portion of the sleeve so that resistance to flow through the fuel lift Venturi tube is increased by the downward movement of the sleeve, and means adapted to be actuated at will either to open the last mentioned opening and close the fuel lift Venturi tube or to close said last mentioned opening and open the fuel lift Venturi tube.
5. A carburetor comprising upper and lower portions secured together, a fuel chamber in the lower portion having a sleeve projecting upwardly above the fuel level, an actuating rod projecting through said sleeve, a tube projecting from the upper portion to below the fuel level and having a fuel outlet at its upper end, said tube and sleeve being in substantial alignment, and a perforated piston in said tube adapted to be actuated by said rod.
6. A carburetor comprising upper and lower portions secured together, a fuel chamber in the lower portion having a sleeve projecting upwardly above the fuel level, an actuating rod projecting through said sleeve, a tube projecting from the upper portion to below the fuel level and having a fuel outlet at its upper end, a perforated piston in said tube adapted to be actuated by said rod, and a member carried by said piston and extending into said fuel outlet adapted to control the effective size thereof in accordance with the position of the piston.
7. A carburetor comprising upper and lower portions secured together and having a throttle valve, a fuel chamber in the lower portion, a tube projecting downwardly from the upper portion to below the fuel level, and having a fuel outlet at its upper end, a piston in said tube adapted to be moved progressively with the throttle valve, and means carried by the piston adapted to project through the fuel outlet to modify the effective size thereof in accordance with the throttle valve position.
8. In a carburetor, in combination, an accelerator pump having a perforated piston adapted to provide an enhanced supply of fuel on rapid acceleration, said fuel passing through said piston and through a metering orifice, and an econometer element rigidly carried by said piston and projecting through said orifice to control the effective area thereof in accordance with throttle position.
9. A fuel lift carburetor comprising a main Venturi tube, a fuel lift Venturi tube, a mixing chamber into which said Venturi tubes deliver, a valve responsive to suction in the mixing chamber and adapted to impede the flow through the fuel lift Venturi tube to a degree depending upon said suction, a throttle valve controlling the outlet from said mixing chamber, a duct extending

from the mouth of the fuel lift Venturi tube to the engine side of the throttle valve, and adjustable means adapted to control the flow through said duct.

10. A fuel lift carburetor comprising a fuel chamber, a main Venturi tube, a fuel lift Venturi tube, ducts connecting the throats thereof to the fuel chamber, a mixing chamber into which the Venturi tubes deliver, a throttle valve controlling the outlet from said mixing chamber, a duct extending from the outer end of said fuel lift Venturi tube to the engine side of the throttle valve, and a screw for adjusting the flow through the last-mentioned duct.

11. A carburetor comprising a pair of complementary sections secured together, a fuel chamber in one section having a sleeve projecting upwardly above the fuel level in said chamber, an actuating rod projecting through said sleeve and guided thereby, a tube carried by the other section and projecting into said chamber to a point below the fuel level therein, said tube telescoping the upper end of said sleeve and having a fuel outlet at its upper end, and pump means guided by said tube, said means and said rod having surfaces conformed to provide a satisfactory, operative connection therebetween irrespective of misalignment between said tube and said sleeve.

12. A fuel lift carburetor comprising a main Venturi tube, a fuel lift Venturi tube, a mixing chamber into which said Venturi tubes deliver, a throttle valve in said mixing chamber, a metering orifice limiting the admission of atmospheric air to said fuel lift Venturi tube, a chamber located between said orifice and the inlet to said last-mentioned Venturi tube, and a duct establishing communication between said last-mentioned chamber and the engine side of the throttle valve.

13. A fuel lift carburetor comprising a fuel chamber, a main Venturi tube supplied from said chamber, a fuel lift Venturi tube for creating subatmospheric pressure in said chamber whereby fuel is drawn thereinto from a main fuel supply tank located at a distance from said chamber, a mixing chamber into which said Venturi tubes deliver, a throttle valve in said mixing chamber, and a by-pass operable at nearly closed throttle positions for reducing the effectiveness of the fuel lift Venturi tube.

14. A fuel lift carburetor comprising a main Venturi tube, a fuel chamber from which said main Venturi tube is supplied, a fuel lift Venturi tube for creating a subatmospheric pressure in said fuel chamber whereby fuel is drawn thereinto from a main fuel supply tank, a mixing chamber into which said Venturi tubes deliver, a throttle valve in said mixing chamber, and a duct communicating between the inlet of the fuel lift Venturi tube and the engine side of the throttle valve.

15. A fuel lift carburetor comprising a main Venturi tube, a fuel chamber from which said Venturi tube is supplied, a fuel lift Venturi tube for creating a subatmospheric pressure in said chamber whereby fuel is drawn thereinto from a main fuel supply tank, a mixing chamber into which said Venturi tubes deliver, a valve responsive to suction in the mixing chamber and adapted to impede the flow through the fuel lift Venturi tube to a degree depending upon said suction, a throttle valve controlling the outlet from said mixing chamber, and a duct extending from the inlet of the fuel lift Venturi tube to the engine side of the throttle valve.

16. A carburetor comprising upper and lower portions secured together, a fuel chamber in the lower portion having a part projecting upwardly above the fuel level, an actuating rod projecting through said part, a second part projecting from the upper portion to a point below the fuel level and providing a cylinder, said cylinder having a fuel outlet at its upper end, said parts being in substantial alignment, and a perforated piston 10 in said cylinder adapted to be actuated by said rod.

17. A fuel lift carburetor comprising a main Venturi tube, a fuel lift Venturi tube, a mixing chamber into which said Venturi tubes deliver, a throttle valve in said mixing chamber, a metering orifice limiting the admission of atmospheric air to said fuel lift Venturi tube, means for varying the size of said orifice, a chamber located 15 between said orifice and the inlet to said last

mentioned Venturi tube, and a duct establishing communication between said last mentioned chamber and the engine side of the throttle valve.

18. A fuel lift carburetor comprising a fuel chamber, a main Venturi tube supplied from said chamber, a fuel lift Venturi tube for creating sub-atmospheric pressure in said chamber, whereby fuel is drawn thereinto from a main fuel supply tank located at a distance from said chamber, a mixing chamber into which said Venturi tubes deliver, a throttle valve in said mixing chamber, a by-pass operable at nearly closed throttle positions for reducing the effectiveness of said fuel lift Venturi tube, and other means 10 operable at open throttle positions for reducing the effectiveness of the fuel lift Venturi tube. 15

ROBERT F. BRACKE.
